REFRIGERATING APPARATUS

Harry B. Hull, Dayton, Ohio, assignor, by mesne assignments, to General Motors Corporation, a corporation of Delaware

Application May 28, 1930, Serial No. 456,683

11 Claims. (Cl. 62—118)

This invention relates to refrigerating apparatus and methods and particularly to that type of apparatus and method which maintains automatically two zones at different temperatures.

5 An object of this invention is to provide a method and apparatus for maintaining two or more zones at different temperatures by means of a closed circulating system containing a volatile refrigerant at the same pressure throughout the closed system and in which the operation of the closed system is controlled in accordance with conditions prevailing in the apparatus.

Further objects and advantages of the present invention will be apparent from the following 15 description, reference being had to the accompanying drawing, wherein a preferred form of the present invention is clearly shown.

In the drawing:

Fig. 1 is a view, partly in vertical cross-section, 20 and partly in elevation, and partly diagrammatic, of an apparatus embodying features of this invention;

Fig. 2 is an enlarged elevation of a portion of Fig. 1; and

25 Fig. 3 is a vertical cross-section taken transversely to Fig. 2.

According to this invention, two or more zones may be maintained at relatively low and relatively higher refrigerating temperatures by cyclically exposing a volatile refrigerant to a vaporizing action in one of said zones and condensing the refrigerant in another of said zones, while said refrigerant is maintained throughout at substantially the same pressure, by utilizing conditions in the method or apparatus for restricting the normal flow of refrigerant.

Features of this invention may thus include means for maintaining a first zone 20 at a relatively low temperature and means 22 for maintaining a second zone or body to be cooled 21 at a higher temperature. The means 22 preferably is a closed circulating system, which may contain a volatile refrigerant substantially at the same pressure (neglecting slight hydrostatic heads) throughout the closed system 22. Means 22 may also include an evaporator 23 adapted to perform the cooling for the zone 21. The means 22 may also include a condenser 24 in the first zone 20. A connection for the flow of refrigerant between the evaporator and the condenser may include a liquid line 25 and a vapor line 26 so that refrigerant condensed in the condenser 24 may flow through the line 25 to the evaporator 23 and the refrigerant evaporated in the evaporator

28 may pass as a vapor through the line 26 to the condenser 24.

The normal flow of refrigerant between the condenser 24 and the evaporator 23 may be varied in accordance with conditions in the apparatus. That is, the flow which normally would take place under temperature conditions prevailing in the apparatus may be varied in order to maintain the desired temperature condition or differential in the apparatus. As a specific example, means 27, responsive to pressure conditions in the closed circulating system 22, may be provided for varying the normal flow of refrigerant. Preferably this normal flow of refrigerant is varied in the vapor line 26 by throttling the flow of vaporized refrigerant in the vapor line 26. This may be accomplished by providing a bellows 28, responsive to pressure conditions in the closed system 22 for operating a valve 29 in the vapor line. Thus it is to be seen that when the valve 29 partly or completely throttles the line 26, further evaporation in the evaporator 23 causes liquid refrigerant from the evaporator to flow in the insulated line 25 towards the condenser 24. This varies the amount of liquid refrigerant in the evaporator 26 and thus varies the cooling capacity of the evaporator.

The bellows 28 may be made responsive to pressure conditions in the system 22 by providing a passageway 30 connected to the portion 31 of the vapor line 26. A spring 32 is adapted to resist the operation of the bellows 28, so that when the pressure in the closed system 22 drops, the bellows 28 tends to close the valve 29, and when the pressure in the system 22 increases, the bellows 28 tends to open the valve 29. A manual adjustment 33 may be provided for varying the tension of the spring 32 in order to vary the conditions under which the valve 29 operates, to suit the individual requirements of the user.

The zone 20 may be maintained at a relatively low temperature by any suitable means. Thus a coil 34 may be placed in thermal contact with the condenser 24. The coil 34 may be refrigerated by any suitable means. Thus it may be refrigerated by providing a primary refrigerant evaporator, including, for example, an expansion valve 35 which expands refrigerant entering the pipe 36 leading to the coil 34. The expanded refrigerant may pass through the pipe 37 from the coil 34 to any suitable liquefying means such as a compressor 38 which delivers compressed refrigerant to a condenser 39 discharging into a liquid refrigerant receiver 40. The receiver 40 may be connected by means of a

liquid refrigerant pipe 41 with the expansion valve 35.

The zone 20 may be maintained at any desired predetermined temperature. Thus it may be maintained at a substantially constant temperature between predetermined temperature limits by any suitable means, such as by a thermostat 42 submerged in the brine 43 surrounding the coil 34. The thermostat 42 may operate a snap switch 44 through the medium of an expandible bellows 45 connected by the line 46 with the thermostat 42. The snap switch 44 may control the starting and stopping of the motor 47 which drives the compressor 38, thus maintaining the zone 20 within predetermined temperature limits.

If the zones 20 and 21 are part of a domestic mechanical refrigerator, it may be desirable to provide means for freezing ice cubes or the like. This may be accomplished by providing sleeves 20 50 in the brine tank 51 for the reception of ice cube trays 52. The zone 21 may be formed by the lining 55 which forms a food compartment and is insulated by means of the insulation 53. The zone 20 may be insulated from the zone 21 25 by means of the insulation 54.

In this particular embodiment, the zone 21 tends to be maintained at a predetermined temperature by the variation of the cooling action of the evaporator 23 acting under the influence 30 of the means 27. Thus when the evaporator 23 is cooled sufficiently by the evaporation of refrigerant, the pressure in the system 22 drops to such a point that the valve 29 is partly or wholly closed. Any evaporation in 23 in excess of that 35 required to produce the amount of vapor passing the valve 27 tends to create an excessive amount of vapor in the upper part of the evaporator 23. This forces liquid refrigerant from the evaporator 23 through the insulated pipe 25 towards the condenser 24. Since the amount of liquid refrigerant in the evaporator 23 is thus reduced, its cooling action on the zone 21 is reduced. On the other hand, when the temperature of the refrigerant in the evaporator 23 rises, the pressure 40 45 in the system 22 also rises, so that the valve 29 is opened and permits all of the liquid refrigerant possible to flow into the evaporator 23. This increases the cooling power of the evaporator to its maximum capacity at the refrigerant temperature prevailing. This action tends to maintain the average temperature of the evaporator 23 and of the zone 21 substantially constant. This permits the maintenance of the food compartment at any desired temperature independently 50 55 of the temperature prevailing in the zone 20.

While it may be stated that the pressure prevailing in the closed circulating system 22 is governed partly by the temperature in the evaporator 23 and partly by the temperature in the condenser 24, it is to be noted that the temperature of the liquid in the system 22 is the predominating and practically sole factor in the determination of the pressure in the system 22. For this reason, when the temperature in the zone 21 tends to rise above the limit desired, the liquid in the evaporator 23 is also heated. This creates a relatively high refrigerant pressure in the system 22 and opens the valve 29, thus admitting all of the liquid refrigerant into the evaporator 23 and increasing its cooling capacity to a maximum in order that it may prevent the undesired rise in temperature in the zone 21. Conversely, when the temperature in the zone 21 tends to fall below the desired limit, 75 the liquid refrigerant in the system 22 is also

cooled and its pressure is likewise reduced. This permits the valve 29 to close and thus eventually force some of the liquid refrigerant from the evaporator 23 into the line 25. This decreases the cooling capacity of the evaporator 23 and prevents the undesired fall in temperature in the zone 21.

While the form of embodiment of the invention as herein disclosed, constitutes a preferred form, it is to be understood that other forms might be adopted all coming within the scope of claims which follow.

What is claimed is as follows:

1. A refrigerating apparatus comprising means for maintaining a first zone at a relatively low temperature, means for maintaining a second zone at a higher temperature, said last named means including a closed circulating system containing a volatile refrigerant at substantially the same pressure throughout the closed system, and having an evaporator in said second zone and a condenser in said first zone, a connection between said evaporator and condenser, and means responsive to pressure conditions in said closed circulating system for varying the amount of liquid refrigerant in said evaporator.

2. A refrigerating apparatus comprising means for maintaining a first zone at a relatively low temperature, means for maintaining a second zone at a higher temperature, said last named means including a closed circulating system containing a volatile refrigerant at substantially the same pressure throughout the closed system, and having an evaporator in said second zone and a condenser in said first zone, a liquid line and a vapor line between said evaporator and condenser, and means responsive to pressure conditions in said closed circulating system for causing liquid refrigerant from said evaporator to flow towards said condenser in said liquid line.

3. A refrigerating apparatus comprising means for maintaining a first zone at a relatively low temperature, means for maintaining a second zone at a higher temperature, said last named means including a closed circulating system containing a volatile refrigerant at substantially the same pressure throughout the closed system, and having an evaporator in said second zone and a condenser in said first zone, a liquid line and a vapor line between said evaporator and condenser, and means responsive to conditions in said apparatus for causing liquid refrigerant from said evaporator to flow towards said condenser in said liquid line.

4. A refrigerating method which comprises maintaining a first zone at a relatively low refrigerating temperature, and maintaining a second zone at a higher refrigerating temperature by cyclically exposing a volatile refrigerant to a vaporizing action in said second zone and condensing said refrigerant in said first zone, said refrigerant being maintained at substantially the same pressure while vaporizing and condensing and utilizing the pressure conditions of said refrigerant to vary the amount of liquid refrigerant exposed to vaporizing action.

5. A refrigerating system of the thermo siphon type comprising an expansion zone, a condensing zone, means for restricting the flow of gas from the expansion zone to the condensing zone and an insulated connection between the condensing zone and the expansion zone for minimizing heat flow into the liquid refrigerant flowing from the condensing zone to the expansion zone.

6. A closed thermo siphon type of refrigerat-

ing system having a condensing element and a heat absorbing element receiving liquid refrigerant by gravity circulation from said condenser and in which a volatile refrigerant is utilized and in which the refrigerant flows in a predetermined path, the method of regulating the temperature of the heat absorbing element of such system which comprises throttling the flow of gaseous refrigerant in one direction and causing a non-gravitational flow of liquid refrigerant from the heat absorbing element to the condensing element of the system in the opposite direction.

7. A closed thermo siphon type of refrigerating system having a condensing element and a heat absorbing element receiving liquid refrigerant by gravity circulation from said condenser and in which a volatile refrigerant is utilized and in which the refrigerant flows in a predetermined path, the method of regulating the temperature of the heat absorbing element of such system which comprises throttling the flow of gaseous refrigerant from the heat absorbing element to the condensing element in one direction and causing a non-gravitational flow of liquid refrigerant from the heat absorbing element to the condensing element of the system in the opposite direction.

8. A closed thermo siphon type of refrigerating system comprising a condensing element and a heat absorbing element receiving liquid refrigerant by gravity circulation from said condenser and in which a volatile refrigerant flows in a predetermined path, means for throttling the flow of gaseous refrigerant in one direction and means for causing a non-gravitational flow of liquid

refrigerant from the heat absorbing element to the condensing element of the system in the opposite direction.

9. A closed thermo siphon type of refrigerating system comprising a condensing element and a heat absorbing element receiving liquid refrigerant by gravity circulation from said condenser and in which a volatile refrigerant flows in a predetermined path, means for throttling the flow of gaseous refrigerant in one direction 10 means for causing a non-gravitational flow of liquid refrigerant from the heat absorbing element to the condensing element of the system in the opposite direction and an insulated connection between the heat absorbing element and the condensing element.

10. In a closed thermo siphon type refrigerating system the process of refrigeration which comprises gravitationally circulating volatile refrigerant from a condensing zone through a non-heat exchanging zone to a heat interchanger and automatically varying the surface of contact between the liquid refrigerant and the heat interchanger.

11. In a dual refrigerating system, in combination, a primary refrigerating means having a zone at relatively low temperature, a secondary closed circuit having a volatile refrigerant therein and having a condenser in thermal exchange with said zone, an evaporator in thermal exchange with a body to be cooled, and means for causing the liquid level to be varied in said evaporator in response to vapor-pressure characteristics of said secondary closed circuit.
